SACCHARINE TRAP.

1,415,818.

Specification of Letters Patent. Patented May 9, 1922.

Application filed November 3, 1919. Serial No. 335,303.

To all whom it may concern:

Be it known that I, GODFREY ENGEL, Sr., citizen of the United States, and resident of Brooklyn, county of Kings, and State of New York, have invented certain new and useful Improvements in Saccharine Traps, of which the following is a specification.

The present invention is a saccharine trap 10 designed more particularly for collecting the entrainment between the evaporator and the condenser.

The objects of the invention are to provide a simple and practical construction which 15 will hold and retain the entrainment out of the path of the vapor current so that once caught the entrainment will not again be picked up and carried away with the vapor.

In the construction herein disclosed I 20 have shown the trap in the form of an annular chamber interposed in the neck of the evaporator between the evaporator and condenser and provided with ribs or baffles for collecting the syrup in a pocket disposed below and out of the direct current of the 25 vapor.

In the drawing, which illustrates but one 30 exemplification of the invention, Figure 1 is a vertical sectional view of the complete apparatus.

Figure 2 is a horizontal sectional view taken on substantially the plane of line 2—2 of Figure 1.

The evaporator is shown as of the usual 35 construction, consisting of a shell or body 5 provided with an outlet neck 6. This neck is formed with a vertically disposed discharge passage 7 in one side thereof and baffles 8 are shown provided on the opposite 40 vertical edges of this passage. These baffles may be provided by simply turning out the walls of the neck at the opposite edges of the opening. In addition I have shown these baffle walls as provided with 45 inwardly projecting angularly disposed ribs or flanges 9, which exert a further baffling effect upon the outflowing vapor. Surrounding the neck portion of the evaporator is an annular wall 10 which, with the wall 50 of the neck, forms an annular chamber 11 constituting the trap proper. The two annular walls described are shown connected at the bottom by inclined wall 12, which forms one side of a collecting or drainage 55 pocket in the bottom of the trap. The trap

is closed at the top by a cover 13, which for the purposes of repair and the like is made removable, as indicated.

14 designates the condenser which is shown connected with the trap by means 60 of a conduit 15. This conduit enters the trap at a point substantially diametrically opposite the discharge opening 7 and at this outlet point additional baffle walls are provided, said baffle walls consisting of a flange 65 16 projecting inwardly into the annular chamber around the outlet opening.

In the illustration I have also shown the outer surrounding wall provided with inwardly projecting vertical ribs or flanges 17 70 extending into the annular chamber at opposite sides of the discharge opening 7 and down below the lower edge of said openings (Figure 1) so as to conduct the entrainment below the opening and so out 75 of the direct path of the vapor. In this way the entrainment is in effect positively carried away from the vapor current and the possibility of its being again caught up and carried off by the vapor is thereby eliminated.

With the construction described the vapors passing from the neck of the evaporator to the condenser are subjected to a baffling action and the entrainment is 85 caught by the ribs or baffling walls described, all of which drain into the annular pocket provided in the bottom of the trap. The accumulation of entrainment is drained off from the bottom of the trap in any suitable 90 way and it will be noted that the entrainment as it collects is out of the path of the current of vapor and so is not affected by the constant flow of vapor.

What I claim is:

1. A saccharine trap having a conduit for the flow of vapor in a substantially horizontal plane constructed to produce a change in direction in the flow of vapor and having an entrainment collecting chamber open 100 thereto at the point of such change in direction but partly below the direct path of vapor flow therethrough and an entrainment trapping pocket on an outer wall of the conduit substantially at the point of 105 change in direction of the vapor flow to thereby catch the heavier particles thrown outward by centrifugal force from the vapor by the change in direction of movement and extending from the horizontal 110

- plane of direct vapor flow down into the entrainment collecting chamber to thereby catch the heavier entrainment carried by the vapor and thrown outwardly by centrifugal force and to hold the same at one side of the vapor path and conduct it directly down into the entrainment collecting chamber.
2. In a saccharine trap an annular wall having an opening in one side thereof and outwardly extending flanges at opposite edges of said opening and projecting outwardly beyond the annular wall and entrainment catching ribs on the inner faces of said outwardly projecting flanges and providing entrainment collecting pockets adapted to drain down outside the annular wall, an entrainment collecting chamber at the foot of said annular wall to catch the drain from said pockets and a wall surrounding said annular wall and providing in conjunction therewith a vapor conduit, and upright ribs on the inner face of said outer surrounding wall at opposite sides of the opening in the inner wall and forming additional pockets for the trapping of entrainment.
3. In a saccharine trap an annular wall having an opening in one side thereof and outwardly extending flanges at opposite edges of said opening and projecting outwardly beyond the annular wall and entrainment catching ribs on the inner faces of said outwardly projecting flanges and providing entrainment collecting pockets adapted to drain down outside the annular wall, an entrainment collecting chamber at the foot of said annular wall to catch the drain from said pockets and a wall surrounding said annular wall and providing in conjunction therewith a vapor conduit, and upright ribs on the inner face of said outer surrounding wall at opposite sides of the opening in the inner wall and forming additional pockets for the trapping of entrainment.

In witness whereof I hereunto set my hand, this 31st day of October, 1919.

GODFREY ENGEL, Sr.
